UNITED STATES PATENT OFFICE.

GERALD W. HART, OF WEST HARTFORD, CONNECTICUT, ASSIGNOR TO THE HART MANUFACTURING COMPANY, OF HARTFORD, CONNECTICUT, A CORPORATION OF NEW JERSEY.

THERMOSTATICALLY-CONTROLLED SWITCH.

Application filed November 16, 1923. Serial No. 675,092.

This invention relates to circuit controlling apparatus and includes various features of novelty and advantage which find peculiar adaptation in an apparatus for controlling, by means of a temperature responsive device, the heat of an electric heater or oven.

The aim of the invention is to provide an apparatus of this sort which is characterized by its extreme simplicity in construction, its compactness in arrangement, neatness in appearance, its efficiency in operation, the ease and facility with which it may be adjusted and set to operate at any predetermined desired temperature, and by its strength and durability.

As will be seen from the following detailed description, my improved apparatus comprises but a relatively few number of parts, each of which is of simple construction, and these parts are so arranged that injury thereto cannot result due to excessive temperatures. The device may be very quickly set so as to operate with accuracy and sensitivity.

The above and other objects of the invention are obtained in the structure shown in the accompanying drawings wherein is illustrated one of the embodiments which the present invention may take. In these drawings:

Figure 1 is a view in side elevation of my improved apparatus;

Fig. 2 is a central longitudinal section therethrough;

Fig. 3 is a plan view with the cover removed; and

Fig. 4 is a detailed view, being taken on line 4-4 of Fig. 2.

Referring to the drawings in detail, my improved apparatus includes an electric switch having a pair of stationary terminals or contacts 10 and 11 and a switch arm 12 positioned therebetween; a thermostatic device comprising, in the present instance, a metal tube 13 and a carbon rod 14 therein; and a connection through which the thermostatic device moves the switch arm, this connection here being shown in the form of a plunger 15.

The switch elements are mounted on a plate 20 of insulating material located within a base 21 of any suitable construction. The stationary contacts 10 and 11 are respectively carried for adjustment by the strip

22 and the bracket 23 secured to the insulating plate 20. The switch arm 12 is pivoted in the up-turned end of the bracket 19. In the present instance, this bracket has an opening 24 and the end of the switch arm is notched, as at 25, so that the switch arm may be hooked into the opening. The free end of the arm carries a circuit closing member or pin 26 which is suitably insulated from the arm. The circuit closing member 26 is normally urged in the direction of the upper contact 11 by a spring 27 which also serves as a conducting member. One end of the spring is connected to and in contact with the pin 26, and the other end of the arm has sliding engagement in the groove 28 of a contact strip or plate 29. The arrangement of the spring 27 is of advantage in that the two functions of urging the switch arm upwardly and connecting the pin 26 to a source of current are obtained in a very simple manner. Owing to the engagement of the spring in the groove 28, disarrangement of the spring is obviated. It will be seen, particularly from Fig. 2, that the arm is carried about the plunger 15. Cooperating with the arm 12 adjacent its pivotal point is the free end of a relatively shorter lever 30 which is pivoted as at 31 in a bracket 19 through which the plunger slides. This lever extends through an elongated slot 33 in the plunger, there being such clearance between the lower side of the lever and the lower end of this slot that there is never any engagement therebetween so that injury, which might otherwise result from the thermostatic device raising the plunger to extreme position, is guarded against.

The tube 13 of the thermostatic device is preferably of a material having a high coefficient of expansion while the rod 14 therein is of a material of relatively low coefficient of expansion, for instance carbon. The tube 13 may be screwed into the base as shown. The plunger 15 has a head 35 on its lower end which is adapted to engage against, but which is not connected to, the rod 14. Normally, this plunger is urged into engagement with the rod by a spring 36. For the purpose of varying the effective length of the plunger and thereby adjust the device to operate at any predetermined temperature, there is provided in the upper end of the plunger an adjustable member which

is here shown as being in the form of a screw 40 screwed directly into a recess in the upper end of the plunger. The lower end of this screw is adapted to protrude into the slot 33 and engage the upper edge of the lever 30 somewhat adjacent its pivotal point 31. The screw 40 is preliminarily adjusted within the plunger to determine the range of temperature within which the thermostatic device will actuate the switch. In order to set or regulate this screw so that the thermostatic device will actuate the switch at any desired predetermined temperature within the selected range, the screw is connected to a rotatable cover 41 which carries one element of temperature indicating means. This element, in the present instance, takes the form of a scale 42 cooperating with an indicating mark 43 on the base. This cover, it will be seen, in addition to serving as a means for setting the device to operate at any desired temperature, houses the switch mechanism. The cover may be adjustably connected to the screw in any suitable manner but, by preference, the cover is provided with a rotatably adjustable lug 44 adapted to engage in the kerf of the screw 40. This lug is secured to a plate 45 journaled in the top of the cover and is rotatably held at the top and bottom by plates 46 and 47 and screws 48. The plate 45 is slightly thinner than the cover so that the clamping plates 46 and 47 will engage the cover, thereby clamping the lug 44 in adjusted position. The cover is provided with circumferential slots 49 in which engage the ends of screws 50 so that the cover may be rotated through a given arc, but cannot be accidentally displaced.

The operation of the device is briefly as follows. The stationary contacts 10 and 11 may be electrically connected to a solenoid operated switch which controls the heating element of a range, for instance, in such manner that when the circuit closing member 26 is brought into engagement with the contact 11, the solenoid operated switch is operated to throw the current onto the heating element of the range, and the current, through the contact 11, is broken, and when the switch arm is thrown into engagement with the lower contact 10, the remote switch is again operated to throw the heat off of the oven, and the circuit is broken through the contact 10. This application of the switch is stated by way of illustration only. Assuming that the range of temperature within which it is desired to maintain the heat of the oven has been selected, the thermostatic device is heated up as by placing it within a chamber, the temperature of which can be accurately controlled, or within the oven itself, to a predetermined temperature within the selected range. The cover 41 will be removed and the screw 40 will be so adjusted that when the predetermined temperature has been reached the screw will engage the lever 30 and throw the switch closing element 26 down into engagement with the contact 10, and when the chamber cools below that temperature, the thermostatic device will raise the screw out of engagement with the lever 31 permitting the spring 27 to throw the switch arm upwardly thereby bringing the circuit closing member 26 into engagement with the upper contact 11. The cover will now be set so that that indicating mark on the scale 42 corresponding to the temperature at which the device is being set registers with the indicating mark 43, and then the lug 44 is rotatably adjusted relative to the cover so that this lug may engage in the kerf 40; or, if preferred, the device may be set by first setting the cover so that the scale 42 will indicate that temperature at which the device is to be set, and then turning the lug 44 while it is within the kerf 40 so as to adjust the screw to a position where the thermostatic device will operate at the selected temperature.

Assuming that the device has been adjusted, as just described, so that the effective range of temperature is between 400 and 600 degrees, and that the pointer has been set, say on the mark indicating 450 degrees, it will be seen that when the oven, for instance, to which the device is applied, reaches 450 degrees, the tube 13 will have been elongated to such an extent that the plunger is lowered to a point where the lower end of the screw 40 engages and depresses the lever 30 and the switch arm 12, bringing the circuit closing member 26 into engagement with the lower contact 10. The current on the heating element of the oven will now be thrown off. Should the oven continue to heat up after the switch arm has thus been thrown, no damage can result to the switch parts for the thermostatic device will leave the plunger 15 without exerting any pull on it. In this case, the plunger will be suspended on the level 14, and the only downward force exerted will be the compression of the spring 36 which is not sufficiently strong to jam the parts. After the oven cools off, the tube 13 will contract, thereby raising the carbon rod 14, and when a temperature of approximately 450 degrees is reached, the plunger will be raised to move the screw out of engagement with the lever 30, and then the switch arm, under the influence of the spring 27, will be thrown into engagement with the contact 11 and the controlling mechanism with which the switch is associated will throw the current onto the heating element. Should the temperature of the oven fall below 450 degrees, in which event the tube 13 would be further foreshortened, no injury or jamming of the switch parts would result owing to the fact that there

is sufficient clearance between the lever 30 and the lower end of the slot 33. I have found, in actual practice, that the temperature of the oven may be controlled within 5 very small limits.

It will be seen from the foregoing description, taken in connection with the illustrations of the accompanying drawing, that my improved apparatus is very simple in 10 construction and effective in operation. The adjustment and setting of the device may be very conveniently made. Owing to the arrangement of the lever 30 and the switch arm 12, movement of the plunger is 15 bounded, so that for a very slight movement of the plunger there is effected a larger movement of the contact end of the switch arm, which means that the switch may be controlled with greater nicety. Preferably, 20 there will be provided on each of the opposite sides of the cover 41 a scale such as shown at 42. Associated with each scale will be an indicating mark carried by the base. In the present instance, the indicating 25 mark on one side is designated by the numeral 43, as heretofore described, and that on the other side by the numeral 43' (see Fig. 3). The purpose of providing these two scales or temperature indicating means is to 30 adapt the arrangement for both right hand and left hand ranges.

I claim as my invention:

1. In an apparatus of the character described, a base, a thermostat to one side of 35 said base, an electric switch mounted on the other side of said base, a connection actuated by said thermostat to control said switch, a cup-like cover rotatably mounted on said base and housing said switch, and 40 means cooperative with said cover to adjust the effective length of said connection, said cover being provided with graduations co-operating with said base to indicate the adjustment of said connection.

2. In an apparatus of the character described, a base, a thermostat, an electric switch, a plunger constituting a connection 45 between said thermostat and said electric switch, a screw carried by said plunger to 50 vary the effective length thereof, a cover rotatably mounted on said base, means for adjustably connecting said cover to said screw, and means for indicating the adjustment of said screw including a scale and an 55 indicating mark, one of which is carried by said cover.

3. In an apparatus of the character described, a base, a thermostat, an electric 60 switch, a plunger constituting a connection between said thermostat and said electric switch, a screw carried by said plunger to 65 vary the effective length thereof, a cover rotatably mounted on said base, a lug adjustably carried by said cover and adapted 70 to engage in the kerf of said screw, and

means for clamping said lug to said cover in adjusted position.

4. In an apparatus of the character described, a base, a thermostat, an electric switch, a plunger constituting a connection 70 between said thermostat and said electric switch, a screw carried by said plunger to vary the effective length thereof, a cover rotatably mounted on said base, means for adjustably connecting said cover to said 75 screw, means for indicating the adjustment of said screw including a scale and an indicating mark, one of which is carried by said cover, and means for limiting the extent of rotation of said cover.

5. In an apparatus of the character described, a base, a temperature change responsive device located to one side of said base, an electric switch mounted on the other side of said base and including a pivoted 80 arm, a connection between said thermostat and arm extending through said base and including an adjustable member for varying the effective length of said connection and engaging said arm to that side opposite to 85 that of said device, a cover rotatably mounted on said base and housing said switch and adjustably connected to said member, and means carried in part by said cover for indicating the setting of said connection.

6. In an apparatus of the character described, a base, a thermostat, an electric switch mounted on said base, a connection between said thermostat and said switch and including an adjustable member for varying 100 the effective length of said connection to determine the range of operation, a cover rotatably mounted on said base and housing said switch and adjustably connected to said member to adjust the same to any desired 105 temperature within the selected range, said cover being provided with graduations co-operating with said base to indicate the adjustment of said connection.

7. In an apparatus of the character described, a base, an electric switch thereon having a pair of slightly spaced apart contacts, a pivoted switch arm having at its free end a circuit closing member adapted 110 to engage said contacts, a relatively short lever pivoted to said base and having its free end in engagement with said arm adjacent the fulcrum of the latter, a spring normally urging said arm in a direction towards one 115 of said contacts, a thermostatic device, and a plunger between said lever and device arranged to throw said switch into engagement with the other of said contacts, said plunger having an elongated slot through 120 which said lever extends.

8. In an apparatus of the character described, a base, an electric switch thereon having a pair of slightly spaced apart contacts, a pivoted switch arm having at its 125 free end a circuit closing member adapted

- 4
- to engage said contacts, a relatively short lever pivoted to said base and having its free end in engagement with said arm adjacent the fulcrum of the latter, a spring 5 normally urging said arm in a direction towards one of said contacts, a thermostatic device, and a plunger between said lever and device arranged to throw said switch into engagement with the other of said contacts, said plunger having an adjustable member adapted to engage said lever.
9. In an apparatus of the character described, a base, an electric switch thereon having a pair of slightly spaced apart contacts, a switch arm pivoted at one end and having a circuit closing member at its free end adapted to engage said contacts, a lever relatively shorter than said switch arm and adapted to engage the latter between its 20 ends, a thermostatic device, and an operative connection between said device and lever, comprising a plunger engaging at one end against said device and having at its other end an adjustable screw engaging said 25 lever, and a cover adjustably associated with said screw and bearing, at least in part, temperature indicating means.
10. In an apparatus of the character described, a base, an electric switch thereon 30 having a pair of contacts, a pivoted arm

having at its free end an insulated circuit closing member positioned between said contacts, a terminal plate having a groove and a current carrying spring having one end slidably engaging in the groove of said plate 35 and electrically connected at its other end to said member and normally urging said arm into one circuit closing position, a thermostat, and a spring pressed connection between said thermostat and arm for moving the latter into its other circuit closing position.

11. In an apparatus of the character described, a base, a thermostat to the rear side of said base, an electric switch mounted on 45 the forward side of said base and including contacts and a switch arm, a connection actuated by said thermostat to control said switch and extending through said base, a cover for said switch and rotatably mounted, 50 a screw for adjusting the relation between said thermostat and switch so that the thermostat will operate the switch at a selected temperature, said screw being connected to said cover and angularly adjustable therewith, and means carried in part by said cover for indicating the angular position of adjustment thereof and the position of adjustment of said screw.

GERALD W. HART.
